UNITED STATES PATENT OFFICE.

CARL A. WISS, OF WEST FORT DODGE, IOWA.

DOOR-HANGER.

1,118,721.

Specification of Letters Patent. Patented Nov. 24, 1914.

Application filed July 7, 1913. Serial No. 777,857.

To all whom it may concern:

Be it known that I, CARL A. Wiss, a citizen of the United States, residing at West Fort Dodge, in the county of Webster and 5 State of Iowa, have invented certain new and useful Improvements in Door-Hangers, of which the following is a specification.

This invention relates to improvements in door hanger and its object is to produce 10 a door so mounted upon the side of the car that it may be slid back and forth on a straight line with but a minimum amount of friction. Specifically, I provide an adjustable runway which is secured to the side of 15 the freight car and in which my door is secured; the runway thus being adapted to accommodate doors of a variety of thicknesses. The door is mounted upon anti-friction elements which rotate in the plane 20 of movement of the door and it is further provided with a plurality of anti-friction elements which are adjustable and which rotate in a plane at right angles to the plane of movement of the door and which may 25 obtain a bearing upon the adjustable runway.

In the drawings which accompany the specification and are a part of the same: Figure 1 is a side elevation of my improved 30 door in position upon a freight car. Fig. 2 is a similar view with the plates that cover the movable parts removed. Fig. 3 is a section taken on line 3—3 of Fig. 2. Fig. 4 is a detail, partly in section, of the anti-friction elements. Fig. 5 is a detail taken on 35 line 5—5 of Fig. 3. Fig. 6 is a section taken on line 6—6 of Fig. 4.

Like reference characters indicate corresponding parts throughout the several 40 views.

1 is the side of a freight car provided with longitudinally extending angle irons 2 and 3, each of which carry, respectively, longitudinally extending angle irons 4 and 5; 45 the angle irons 2 and 4 are adjustable with

relation to each other as shown at 5 and the angle irons 3 and 5 are adjustable with relation to each other as shown at 6, the two sets of angle irons forming an adjustable runway in which my door is disposed. 50 My door is carried upon rollers 7 that travel upon the runway and that are secured in bearings 8 made fast to the door. The plate 9, which is a part of the bearing 8, is formed with elongated slots 10 for the accommodation of bolts 11 upon which rollers 12 are carried that rotate in a plane at right angles to the plane of the door and that obtain a bearing upon the sides of the runway.

To the top of the door a plate 13 is secured which is formed with elongated slots 14 to accommodate bolts 15, which are movable laterally in said slots, and upon said bolts rollers 16 are disposed that may obtain a bearing upon the sides of the runway. 60 For a door of greater thickness than the one illustrated it is but necessary to adjust the angle irons 4 and 5 with relation to the angle irons 2 and 3. The angle irons and movable parts of the door may be covered and protected from dust or from injury by a suitable plate 17 secured to the 65 side of the car.

What is claimed is:—

In a door hanger, longitudinally extending angle irons arranged in pairs, the members of each pair being adjustable with relation to each other, a door provided with rollers operatively associated with one pair of said angle irons and anti-friction elements carried by said door adapted to obtain a bearing upon said angle irons. 75

In testimony that I claim the foregoing as my own I have hereto affixed my signature in the presence of two subscribing witnesses. 80 85

CARL A: WISS.
